ADJUSTABLE HINGE

Sylvester J. Kreiner, Brunswick, Ohio

Application March 28, 1947, Serial No. 737,847

2 Claims. (Cl. 16—129)

1

This invention relates to adjustable hinges for doors and the like, particularly in combination with refrigerator doors, wherein an air-tight seal of the door opening is desired, and in particular, a hinge having base plates fixedly mounted on the door and the frame, the hinge leaves and base plates having cooperating grooves and ribs which enable adjustment of the hinge leaves relative to the base plates without changing the position of the bolts or screws from their original position in the doors or frames.

In hanging the usual door, the door is placed in position in the frame and places for the hinges are marked on both the door and frame, and after cutting recesses in the parts, the hinge plates or leaves are attached by screws and the like. Once the hinge plates are in place, it is very difficult to adjust the positions thereof, because the bolt or screw openings have been formed in the door and frame, and these cannot be changed without changing the location of the hinge. Furthermore, in doors for ice boxes, refrigerators, and freezing compartments, it is absolutely essential to obtain an absolute air-tight seal, and for the reasons stated above, this is substantially impossible with the usual type of hinge. With these and other thoughts in mind, this invention contemplates a hinge having hinge leaves and mounting plates which have cooperating ribs and grooves enabling adjusting the positions of the hinge leaves relative to the mounting plates which have fixed positions.

The primary object of this invention is, therefore, to provide means for mounting hinges on doors, door frames and the like, wherein the position of the hinge may be adjusted to adjust the door in the door opening or frame without changing the position or mounting elements which are fixed in position.

Another object of the invention is to provide means for obtaining positive registration between doors, door frames and door openings by adjusting the positions of the hinges.

Another object of the invention is to provide means in combination with a hinge, whereby the position of a door mounted by the hinge may be adjusted vertically and horizontally.

A further object of the invention is to provide a combination adjustable hinge for doors and the like which is of a simple and economical construction.

Other objects and advantages of the invention will appear from the following description, taken in connection with the drawings, wherein:

Figure 1 is a front elevation of the improved hinge, with parts broken away to show the ribs and grooves, the hinge being mounted on a frame

and a door, parts of which are also broken away.

Figure 2 is a cross-section through the hinge illustrated in Figure 1, taken on line 2—2 of Figure 1, with parts of the door and door frame upon which the hinge is mounted broken away.

Referring now to the drawings, wherein like reference characters indicate corresponding parts, the hinge of this invention includes hinge plates 10 and 11 hingedly connected by a hinge pin 12 through barrels 13, 14 and 15, and base or mounting plates 16 and 17.

In the illustrated hinge, a single forwardly or outwardly offset barrel 13 is formed integrally with the inward edge of one hinge plate 10. The barrels 14 and 15 are attached to an outwardly and forwardly directed flange 18 on the inner edge of the other hinge plate 11 by screws 19. The plate 10 is provided at opposite ends with pairs of bolt slots 20 which extend longitudinally of the plate, and the plate 11 is provided with transversely elongated bolt slots 21. The inner surface of the hinge plate 11 is formed with longitudinally extending grooves defining ribs 22 positioned to engage between ribs 23 defined by grooves formed in the outer surface of the base plate 17. The inner surface of the plate 10 is provided with laterally extending grooves defining ribs 24 positioned to engage between corresponding ribs 24' defined by grooves in the base plate 16.

The bolt holes 25 in the base plate 16 and 26 in the base plate 17 are not slotted, whereby the base plates remain fixed in position on the surfaces of a door 27 and a frame 28; and with the hinge plates 10 and 16 held by bolts 29 and the plates 11 and 17 held by bolts 30. The door may be adjusted vertically by loosening the bolts 29 and moving the plate 10 in relation to the plate 16, and it may also be adjusted laterally by loosening the bolts 30 and moving the plate 11 in a direction across the plate 17. With the door properly adjusted to accurately register with the door opening or frame, the bolts 29 and 30 are tightened so that the grooves and ribs of the hinge and base plates will be positively secured in engagement. With a hinge including these elements, it is, therefore, possible to positively adjust the position of a door in relation to a door opening or frame both vertically and laterally without changing the position of the bolts or screws of the hinges in the door and frame.

It will be understood that modifications may be made in the design or arrangement of the parts without departing from the spirit of the invention.

What is claimed is:

1. In an adjustable hinge, a first hinge leaf comprising a base plate having a side adapted to engage the surface of the object to which said first hinge leaf is to be secured, transverse ribs formed on the other side of said base plate, and a hinge plate overlying said other side of said base plate and formed with transverse ribs selectively engaged between transverse ribs on the base plate, said hinge plate being formed with a longitudinally elongated bolt slot and said base plate being formed with a bolt hole with which the bolt slot is registered, a bolt extending through said bolt slot and through said bolt hole and arranged to be threaded into the object to which said first hinge leaf is to be secured so as to secure said first hinge leaf thereto with said hinge plate adjusted longitudinally of said base plate, a fixed hinge barrel formed on a longitudinal edge of said hinge plate and a hinge pin journalled in said fixed hinge barrel and extending beyond an end of said fixed hinge barrel, a second hinge leaf comprising a second base plate having a side adapted to engage the surface of the object to which said second hinge leaf is to be secured, longitudinal ribs formed in the other side of said second base plate, a second hinge plate overlying said other side of said second base plate and formed with longitudinal ribs selectively engaged between longitudinal ribs on said second base plate, said second hinge plate being formed with a transversely elongated bolt slot registered with a bolt hole formed in said second base plate, a bolt extending through the bolt slot and the bolt hole and arranged to be threaded into the object to which said second hinge leaf is to be secured, an adjustable hinge barrel secured on a longitudinal side edge of the hinge plate of said second hinge leaf, said longitudinally adjustable hinge barrel being journalled on the hinge pin at one end of the hinge barrel of the first hinge leaf and serving to connect the first and second hinge leaves, and securing means securing said adjustable hinge barrel to the hinge plate of the second hinge leaf and to the hinge pin and enabling said adjustable hinge barrel to be adjusted longitudinally on said hinge pin to accommodate a longitudinal adjustment of the hinge plate of the first hinge leaf relative to the base plate of the first hinge leaf.

2. In an adjustable hinge, a first hinge leaf comprising a base plate having a side adapted to engage the surface of the object to which said first hinge leaf is to be secured, transverse ribs formed on the other side of said base plate, and a hinge plate overlying said other side of said base plate and formed with transverse ribs selectively engaged between transverse ribs on the base plate, said hinge plate being formed with a longitudinally elongated bolt slot and said base plate being formed with a bolt hole with which the bolt slot is registered, a bolt extending through said bolt slot and through said bolt hole and arranged to be threaded into the object to which said first hinge leaf is to be secured so as to secure said first hinge leaf thereto with said hinge plate adjusted longitudinally of said base plate, a fixed hinge barrel formed on a longitudinal edge of said hinge plate and a hinge pin journalled in said fixed hinge barrel and extending beyond an end of said fixed hinge barrel, a second hinge leaf comprising a second base plate having a side adapted to engage the surface of the object to which said second hinge leaf is to be secured, longitudinal ribs formed in the other side of said second base plate, a second hinge plate overlying said other side of said second base plate and formed with longitudinal ribs selectively engaged between longitudinal ribs on said second base plate, said second hinge plate being formed with a transversely elongated bolt slot registered with a bolt hole formed in said second base plate, a bolt extending through the bolt slot and the bolt hole and arranged to be threaded into the object to which said second hinge leaf is to be secured, an adjustable hinge barrel secured on a longitudinal side edge of the hinge plate of the second hinge leaf, said longitudinally adjustable hinge barrel being journalled on the hinge pin at one end of the hinge barrel of the first hinge leaf and serving to connect the first and second hinge leaves, and securing means securing said adjustable hinge barrel to the hinge plate of the second hinge leaf and to the hinge pin and enabling said adjustable hinge barrel to be adjusted longitudinally on said hinge pin to accommodate a longitudinal adjustment of the hinge plate of the first hinge leaf relative to the base plate of the first hinge leaf.

nally elongated bolt slot and said base plate being formed with a bolt hole with which the bolt slot is registered, a bolt extending through said bolt slot and through said bolt hole and arranged to be threaded into the object to which said first hinge leaf is to be secured so as to secure said first hinge leaf thereto with said hinge plate adjusted longitudinally of said base plate, a fixed hinge barrel formed on a longitudinal edge of said hinge plate and a hinge pin journalled in said fixed hinge barrel and extending beyond an end of said fixed hinge barrel, a second hinge leaf comprising a second base plate having a side adapted to engage the surface of the object to which said second hinge leaf is to be secured, longitudinal ribs formed in the other side of said second base plate and formed with longitudinal ribs selectively engaged between longitudinal ribs on said second base plate, said second hinge plate being formed with a transversely elongated bolt slot registered with a bolt hole formed in said second base plate, a bolt extending through the bolt slot and the bolt hole and arranged to be threaded into the object to which said second hinge leaf is to be secured, an adjustable hinge barrel secured on a longitudinal side edge of the hinge plate of said second hinge leaf, said longitudinally adjustable hinge barrel being journalled on the hinge pin at one end of the hinge barrel of the first hinge leaf and serving to connect the first and second hinge leaves, and securing means securing said adjustable hinge barrel to the hinge plate of the second hinge leaf and to the hinge pin and enabling said adjustable hinge barrel to be adjusted longitudinally on said hinge pin to accommodate a longitudinal adjustment of the hinge plate of the first hinge leaf relative to the base plate of the first hinge leaf, said securing means comprising a lateral flange formed on the said longitudinal side edge of the hinge plate of the second hinge leaf, screw means extending through said flange, said adjustable hinge barrel being formed with threaded hole means through which said screw means is threaded into clamping engagement with the hinge pin to maintain an adjusted position of the adjustable hinge barrel on the hinge pin.
